UNITED STATES PATENT OFFICE.

CHARLES W. JONES, OF RICHMOND, AND ROBERT R. GORDON, OF GLENALLEN,
VIRGINIA.

RAILROAD SPIKE.

Application filed August 31, 1926. Serial No. 132,870.

This invention relates to railroad spikes of the type disclosed in our prior Patent No. 1,059,875, issued April 22, 1918.

One object of the invention is to provide a spike which may be driven into a tie and firmly anchor a rail thereto but at the same time permitted to be easily withdrawn when removal or adjustment of a rail is necessary.

Another object of the invention is to so construct the spike that it may have firm gripping engagement either with a rail base or fish plate carried by a rail and overlying its base.

Another object of the invention is to permit the spike to be embedded in a tie and prevent it from having movement therein which would permit a rail to work loose and creep or spread.

The invention is illustrated in the accompanying drawings, wherein

Figure 1 is a view showing a rail and a portion of a tie in section with the improved spikes driven into the tie and securing the rail thereto;

Fig. 2 is a view showing the improved spike in front elevation;

Fig. 3 is a transverse sectional view through the spike taken on the line 3—3 of Fig. 2;

Fig. 4 is a view in side elevation illustrating a modified form of spike;

Fig. 5 is a front elevation of the spike shown in Fig. 4;

Fig. 6 is a transverse sectional view taken on the line 6—6 of Fig. 4;

Fig. 7 is a side elevation of another modified form of spike;

Fig. 8 is a front elevation of the spike shown in Fig. 7, and

Fig. 9 is a transverse sectional view taken on the line 9—9 of Fig. 7.

The spike, which is illustrated in Figs. 1, 2 and 3, includes the usual shank 1 which is tapered at its lower end so that it may be readily driven into a tie. At its upper end the shank carries a head 2 which projects forwardly and rearwardly from the shank to provide bills 3 and 4 and also projects from the sides of the shank to provide

overhanging shoulders 5. Referring to Fig. 3, it will be seen that the shoulders 5 extend upwardly at an outward incline and also converge towards the free ends of the bills 3 and 4 in order to permit the head of the

spike to be firmly engaged by the claws of

an extracting bar. At opposite sides the shank 1 carries wings 6 which extend longitudinally of the shank and project transversely therefrom. These wings are of less length than the shank and formed with tapered lower ends so that they may readily enter a tie when the spike is driven into it. The wings are also of less thickness than the spike, as clearly shown in Fig. 1, and at their upper ends are formed with heads 7 extended forwardly but not projecting beyond the front face of the shank. Referring to Fig. 1, it will be seen that the lower faces of the head 7 extend forwardly at an upward incline and in the same plane as the under face of the bill 3, whereas the under face of the bill 4 extends above the plane of the upper faces of the heads 7. These heads 7 have their upper faces curved longitudinally and spaced below the shoulders 5 so that the claws of an extracting bar may engage the under faces of the shoulders and the bar easily rocked to extract the spike.

When the spike shown in Figs. 1, 2 and 3 is in use, a rail 8 is placed upon its supporting ties, one of which is shown in Fig. 1 and indicated by the numeral 9, fish plates may be applied to the rails and bolted thereto in the usual manner. One of the fish plates referred to is shown at the right of the rail in Fig. 1 and indicated by the numeral 10, but it will be understood that, in actual practice, fish plates would be applied to both sides of the rail when used. When a fish plate is employed, the spike will be driven into the tie, as shown at the right in Fig. 1, with a portion of its shank passing through registering recesses formed in the fish plate and base of the rail. The spike is driven tightly into the tie and, when in place, the lower face of its downwardly thickened bill 3 and the lower faces of the heads 7 engage the upper face of the rail base-engaging portion of the fish plate. The rail will, therefore, be very firmly spiked to the tie and will be prevented from having longitudinal or transverse movement. When no fish plates are employed, the spike is reversed when driven into the tie so that the bill 4 instead of the bill 3 will overlap the rail base. Since the under face of the bill 4 is in an elevated plane with respect to the under faces of the bill 3 and head 7, the spike may be very firmly embedded in the tie and tightly grip the rail,

as shown at the left of Fig. 1. When it is necessary to adjust or replace a rail, the claws of an extracting bar are engaged with the head of the spike in straddling relation thereto between the shoulders 5 and the longitudinally curved upper faces of the head 7. The bar may then be swung downwardly to impart an upward movement to its claws and the claws will engage the shoulders 5 and draw the spike upwardly out of the tie.

The spike which is illustrated in Figs. 4, 5 and 6 is very similar to that shown in Figs. 1, 2 and 3 and includes a shank 11 carrying a head 12 and side wings 13. The wings 13 are formed with forwardly projecting heads 14 having longitudinally curved upper faces. At their forward ends the heads are flush with the front face of the shank so that the heads and front face of the shank may engage a side edge face of the rail base for an appreciable distance and firmly brace the rail against transverse movement. The head 12 of the spike projects forwardly to provide a bill 15 adapted to overlie the rail base and the head also extends transversely in overhanging relation to the heads 14 with its side faces 16 under cut and converging towards the end of the bill so that the head of the spike may be firmly gripped by the claws of an extracting bar. This spike will securely hold a rail upon a tie but is not reversible.

In Figs. 7, 8 and 9, the spike illustrated is very similar to the one shown in Figs. 4, 5 and 6 and includes a shank 17 carrying a head 18 which projects forwardly to form a bill 19 and is provided with forwardly ta-

pered under cut sides to provide a shoulder 20. The side wings 21 which project transversely from the shank have their forward bases flush with the front face of the shank instead of their rear faces being flush with the rear face of the shank, and these wings are formed with transversely curved upper edge faces instead of being provided with heads. It should be noted that in each form illustrated the faces of the side wings which project from the sides of the shank at substantially right angles thereto are rounded into the adjacent side faces of the shank so that, when the spike is driven into a tie, the wood will have very close fitting engagement with the spike and a very firm grip obtained upon the spike to prevent it from easily working loose.

Having thus described the invention, we claim:

A spike comprising a shank, a head for said shank having a rail-engaging bill projecting forwardly from the shank and side portions projecting from opposite sides of the shank, and wings extending longitudinally of said shank at opposite sides thereof and projecting transversely therefrom with their rear faces flush with the rear face of the shank, said wings having their upper ends formed with heads spaced below the projecting side portions of the head of said shank with their forward ends terminating flush with the front rail-engaging face of the shank.

In testimony whereof we affix our signatures.

CHARLES W. JONES. [L.S.]
ROBERT R. GORDON. [L.S.]
